UNITED STATES PATENT OFFICE.

HERBERT L. CARMAN, OF NEW YORK, N. Y., ASSIGNOR TO MABIE TODD & CO., OF NEW YORK, N. Y., A CORPORATION OF NEW YORK.

DESIGN FOR A DESK STAND.

Application filed April 20, 1926. Serial No. 17,357. Term of patent 14 years.

To all whom it may concern:

Be it known that I, HERBERT L. CARMAN, a subject of the Kingdom of England, residing at No. 418 West 154th Street, New York city, in the county of New York, whose post-office address is 243 West 17th Street, New York city, in the county of New York and State of New York, have invented a new, original, and ornamental Design for Desk Stand, of which the following is a specification, reference being had to the accompanying drawing, forming part thereof.

I claim:

The ornamental design for a desk stand, as shown.

HERBERT L. CARMAN.
